UNITED STATES PATENT OFFICE.

ADOLF MAYER, OF GENGENBACH, BADEN, ASSIGNOR TO ALFRED SIEDLE,
OF FREIBERG, GERMANY.

DESIGN FOR A GONG FOR TABLE-BELLS.

SPECIFICATION forming part of Design No. 18,493, dated July 31, 1888.

Application filed December 6, 1887. Serial No. 257,167. Term of patent 3½ years.

To all whom it may concern:

Be it known that I, ADOLF MAYER, a subject of the Grand Duke of Baden, residing at Gengenbach, in the Grand Duchy of Baden and German Empire, have invented and produced a new and original Design for Gongs for Table-Bells, of which the following is a specification, reference being had to the accompanying drawings, forming a part thereof, and in which drawings—

Figure 1 is a top plan view, Fig. 2 an under side view, and Fig. 3 is a longitudinal vertical section, of the design.

The object of the design is to produce a table-bell gong of ornamental form; and the design consists of the gong of substantially elliptical form, with its outer or upper surface convex and the contour edge in wave form, and the upper surface provided with irregu-

lar lines, the whole representing conventionally the shell of a tortoise.

In the drawings, A represents the gong, made in substantially elliptical form and with an outer or upper convex face. The contour edge is of wave or similar form, as shown, and the upper surface is provided with irregular lines, the whole representing conventionally the shell of a tortoise.

What I claim is—

The design for a table bell gong consisting of the convex upper face having the contour outline and the surface ornamentation shown and described.

ADOLF MAYER.
